ADJUSTABLE BRAKE SHOE

Steve Schnell, Overland, Mo., assignor to Wagner
Electric Corporation, St. Louis, Mo., a corpora-
tion of Delaware

Application July 13, 1939, Serial No. 284,187

14 Claims. (Cl. 188—79.5)

My invention relates to brakes and more particularly to a brake shoe and adjusting means therefor to compensate for lining wear.

One of the objects of my invention is to provide adjusting means for automatically maintaining both the toe end and the heel end of a pivoted brake shoe a predetermined distance from the drum when the shoe is in "off" position.

Another object of my invention is to provide automatic adjusting means for a brake shoe which is so constructed that the drum engaging portion thereof adjacent the heel is free to be forced into engagement with the drum by a circumferential movement of the shoe, said adjusting means being capable of simultaneously adjusting both the heel end and the toe end so that the drum engaging portion of the entire shoe will be maintained at a constant distance from the drum when the shoe is disengaged.

Other objects of my invention will become apparent from the following description taken in connection with the accompanying drawing in which Figure 1 is a side view of a portion of a brake assembly showing a brake shoe and an adjusting means therefor embodying my invention; Figure 2 is a cross-sectional view taken on the line 2—2 of Figure 1 showing the shoe mounting; and Figures 3, 4, and 5 are cross-sectional views taken on the lines 3—3, 4—4 and 5—5, respectively, of Figure 1 showing details of the adjusting mechanism.

Referring to the figures in detail, I have shown my automatic adjusting means associated with a particular type of brake shoe but it is to be understood that it can be associated with other brake shoe constructions wherein it is found desirable to adjust both the heel end and the toe end of said shoe by a single means in order to compensate for wear of the lining. The particular brake shoe construction shown comprises a web 1 provided at its lower end with an arcuate slot 2 for receiving a bearing member 3 eccentrically mounted on an anchor pin 4 carried by the backing plate 5. The slot 2 permits the web to have limited circumferential movement but restrains the end of the web from radial movement toward the drum. The web is formed with a continuous flange 6 which carries lining 7. The portion of the web from an intermediate point to the pivoted end is provided with a slot 8 and a saw cut 9 in order to free a portion 10 of the web from the main part of the web, thus permitting this portion and the part of the flange and the lining carried thereby to have relative movement with respect to the main part 55 of the web. The bearing member 3 for the shoe

has pivotally mounted thereon on opposite sides of the web two arms 11 which carry at their free ends a pin 12 for engagement with a recess 13 on the free end of the web portion 10. The shoe is shown as actuated into engagement with the drum 14 by means of a fluid motor 15.

When the drum is rotating in the direction indicated by the arrow and the shoe is engaged with the drum, the shoe will have slight circumferential movement with the drum as permitted by the arcuate slot 2. This circumferential movement of the shoe will cause the web portion 10 to rotate the arms 11 and because of their angular relation to the direction of movement of the shoe, the free end of the web portion 10 will be forced outwardly toward the drum, thus causing the lining carried by the web portion 10 to be applied to the drum with a greater force than would be the case if the web portion 10 were integral with the main part of the web 1 of the shoe. The shoe is thus capable of producing a greater braking action because a part of the force tending to move the shoe with the drum is transferred into a radial pressure on the "heel" portion of the lining which is free to move outwardly.

In accordance with my invention I have provided means for automatically and simultaneously adjusting the "off" positions of both the toe end of the brake shoe and the heel end of the brake shoe in order to compensate for wear of the lining. The construction I employ comprises a lever 16 which is pivotally mounted intermediate its ends to the web 1 of the shoe by means of a bolt 17 having an eccentric portion upon which the lever is mounted in order to provide for adjustment of the pivotal axis of the lever with respect to the web. The upper arm 18 of the lever is provided with a projection 19 extending through an opening 20 in the lining carrying flange 6 and lining 7 of the shoe and having its outer end surface flush with the lining surface. The arm 18 cooperates with a stop 21 carried by the backing plate, this stop determining the distance that the shoe can be withdrawn from the drum by means of the retractile spring 22 when the fluid motor 15 is released.

The web 1 carries a pin 23 formed with a V-shaped groove 24 for receiving a V edge 25 on a wedge 26 which is interposed between a portion 27 on arm 18 of the lever 16. The wedge is held in position by a spring 28 having one of its ends connected to the end of pin 23 and its other end connected to a pin 29 carried by the arm 18 of the lever and extending through an opening 30 in the

web. A spring 31 is connected to the wedge and to the lever for moving the wedge relatively to the portion 27 on arm 18 of the lever and pin 23 whenever the lever is moved relative to the pin. 5 A shoulder 32 is provided on the wedge for engagement with the portion 27 on arm 18 to limit the extent of movement of the wedge under the action of spring 31. The lower arm 33 of the lever carries a pin 34 which extends into the lower 10 end of the slot 8 of the web of the shoe for engagement with the web portion 10.

When the adjusting mechanism just described is mounted on the shoe, the shoe is first applied to the drum and then the lever is adjusted by 15 means of the pin 17 so the end surface of extension 19 on the upper arm of the lever engages the drum and the pin 34 on the lower arm of the lever engages the portion 10 of the web. The stop 21 is next positioned so that when the shoe is released, the lining will have the desired clearance 20 with respect to the drum, the shoe being released by pivotal movement about the anchor pin 4 which is adjusted to give proper clearance at the heel of the shoe. When the lining on the shoe 25 begins to wear as a result of braking action, the lever 16 will be moved in a counter-clockwise direction about the pivot pin 17 due to the fact that the extension 19 is not worn as rapidly as the lining and, therefore, will be pushed back even with 30 the lining as the lining wears. Whenever there is any relative movement between the upper arm 18 of the lever and the web, the wedge 26 will take a new position under the operative action of the spring 31 and this new position will be maintained 35 by the spring 28. Since the lever moves relatively to the shoe as the lining wears, the engagement of the lever with the stop 21 will not permit the shoe to move away from the drum as far as it did before and thus the lining wear will be compensated for. As arm 18 is moved due to lining 40 wear over the toe portion of the shoe, there will also be simultaneous movement of the lower arm 33 toward the drum which will adjust the web portion 10 with respect to the main body of the 45 web to compensate for wear of the lining thereon. It is thus seen that whenever there is automatic adjustment of the toe of the shoe to compensate for lining wear, there will be simultaneous adjustment of the heel end of the shoe. It may 50 happen that the rate of wear of the lining at the toe end of the shoe will be greater or less than that at the heel end but this can be compensated for by properly proportioning the lengths of the arms 33 and 18.

55 It is to be noted that the entire adjusting mechanism is simple in construction and is carried entirely by the brake shoe with the exception of stop 21 which is carried by the backing plate. Due to the fact that the adjusting mechanism is carried 60 by the shoe and no adjustment takes place except when the lining wears, the mechanism is not affected by expansion and contraction of the drum during braking action.

65 Being aware of the possibility of modifications in the particular structure herein described without departing from the fundamental principles of my invention, I do not intend that its scope be limited except as set forth by the appended 70 claims.

Having fully described my invention, what I claim as new and desire to secure by Letters Patent of the United States is:

75 1. In braking apparatus, a support, a brake drum, a brake shoe mounted on the support and

provided with drum engaging means, and automatically operable means for maintaining the "off" position clearance between the drum and said drum engaging means substantially constant, said means comprising a lever pivotally carried by the shoe and being so movable as a result of wear of the drum engaging means that different parts of the lever will cause circumferentially spaced apart portions of the drum engaging means to be simultaneously adjusted toward the 10 drum. 5

2. In braking apparatus, a support, a brake drum, a brake shoe mounted on the support and provided with drum engaging means, and automatically operable means for maintaining the "off" position clearance between the drum and said drum engaging means substantially constant, 15 said means comprising a lever pivotally mounted intermediate its ends on the shoe and so cooperating with the drum when the shoe is engaged therewith that it will be moved relatively to the shoe as the result of wear of the drum engaging means, means for causing one end of said lever to adjust the "off" position of one portion of the drum engaging means toward the drum, and 20 means for causing the other end of said lever to adjust the "off" position of another portion of the drum engaging means toward the drum. 25

3. In braking apparatus, a support, a brake drum, a brake shoe mounted on the support and provided with drum engaging means, and automatically operable means for maintaining the "off" position clearance between the drum and said drum engaging means substantially constant, 30 said means comprising a lever pivotally mounted intermediate its ends on the shoe and so cooperating with the drum when the shoe is engaged therewith that it will be moved relatively to the shoe as the result of wear of the drum engaging means, means for causing one end of said lever to 35 adjust the "off" position of one portion of the drum engaging means toward the drum, means for causing the other end of said lever to 40 adjust the "off" position of another portion of the drum engaging means toward the drum, and 45 wedging means for maintaining said lever and shoe in their relatively adjusted positions.

4. In braking apparatus comprising a support, a brake drum, and a brake shoe pivotally mounted at one end on the support for cooperation with the drum, said shoe having the lining carrying part thereof which is adjacent the mounted end portion movable relatively to the body of the shoe and toward the drum when the shoe is applied, 50 automatically operable means associated with the shoe and the support for maintaining a substantially constant "off" position clearance between the unmounted end of the shoe and the drum and between the lining carrying part adjacent the mounted end of the shoe and the drum as the lining on said shoe wears. 55

5. In braking apparatus comprising a support, a brake drum, and a brake shoe pivotally mounted at one end on the support for cooperation with the drum, said shoe having the lining carrying part thereof which is adjacent the mounted end movable relatively to the body of the shoe and toward the drum when the shoe is applied, 60 automatically operable means associated with the shoe and the support for maintaining a substantially constant "off" position clearance between the unmounted end of the shoe and the drum and between the relatively movable lining carrying part of the shoe and the drum as the lining on said shoe wears, said means comprising a lever pivotal- 65

ly carried by the body of the shoe and movable relatively to the shoe only when lining wear occurs.

6. In braking apparatus comprising a support, 5 a brake drum, and a brake shoe pivotally mounted at one end on the support for cooperation with the drum, said shoe having the lining carrying part thereof which is adjacent the mounted end movable relatively to the body of the shoe and toward the drum when the shoe is applied, automatically operable means associated with the shoe and the support for maintaining a substantially constant "off" position clearance between the unmounted end of the shoe and the drum 10 and between the relatively movable lining carrying part of the shoe and the drum as the lining on said shoe wears, said means comprising a lever pivotally mounted intermediate its ends on the body of the shoe, means for moving the lever relatively to the shoe as the lining wears, means for causing one end of said lever when moved to thereby adjust the "off" position of the unmounted end of the shoe toward the drum and means 15 for causing the other end of the lever when moved to thereby adjust the "off" position of the lining carrying part adjacent the mounted end of the shoe toward the drum. 20

7. In braking apparatus comprising a support, 30 a brake drum, and a brake shoe pivotally mounted at one end on the support for cooperation with the drum, said shoe having the lining carrying part thereof which is adjacent the mounted end movable relatively to the body of the shoe and toward the drum when the shoe is applied, automatically operable means associated with the shoe and the support for maintaining a substantially constant "off" position clearance between the unmounted end of the shoe and the drum 35 and between the relatively movable lining carrying part of the shoe and the drum as the lining on said shoe wears, said means comprising a lever pivotally mounted intermediate its ends on the body of the shoe, means for moving the lever relatively to the shoe as the lining wears, means for causing one end of said lever when moved to thereby adjust the "off" position of the unmounted end of the shoe toward the drum, means for causing the other end of the lever when moved to thereby adjust the "off" position of the lining carrying part adjacent the mounted end of the shoe toward the drum. 40

8. In braking apparatus, a support, a brake drum, a brake shoe mounted on the support, said shoe comprising a web mounted at one end for pivotal movement and for circumferential movement, drum engaging means carried by the web and comprising a part secured to the web 50 from an intermediate point to the unmounted end thereof and another part extending over the web from the mounted end toward an intermediate point and free to move relatively to the web and toward the drum, means for applying an outward acting force to said free part when the shoe is applied to the drum, and automatically operable adjusting means for simultaneously maintaining the "off" position clearance of both parts of the drum engaging means substantially constant as said means wears. 55

9. In braking apparatus, a support, a brake drum, a brake shoe mounted on the support, said shoe comprising a web mounted at one end for pivotal movement and for circumferential move- 75

ment, drum engaging means carried by the web and comprising a part secured to the web from an intermediate point to the unmounted end thereof and another part extending over the web from the mounted end toward an intermediate 5 point and free to move relatively to the web and toward the drum, means for applying an outward acting force to said free part when the shoe is applied to the drum, and automatically operable adjusting means for simultaneously 10 maintaining the "off" position clearance on both parts of the drum engaging means substantially constant as said means wears, said adjusting means comprising a lever pivotally mounted intermediate its ends on the web and having a portion engageable with the drum only when the shoe is applied, cooperating means between one end of said lever and the support for adjusting the "off" position of the unmounted end of the shoe toward the drum, and connecting means 15 between the other end of the lever and the free portion of the drum engaging means for adjusting the "off" position of said free portion of the drum engaging means toward the drum. 20

10. In braking apparatus, a support, a brake drum, a brake shoe mounted on the support, said shoe comprising a web mounted at one end for pivotal movement and for circumferential movement, drum engaging means carried by the web 30 and comprising a part secured to the web from an intermediate point to the unmounted end thereof and another part extending over the web from the mounted end toward an intermediate point and free to move relatively to the web and toward the drum, means for applying an outward acting force to said free part when the shoe is applied to the drum, and automatically operable adjusting means for simultaneously maintaining the "off" position clearance of both parts of the drum engaging means substantially constant as said means wears, said adjusting means comprising a lever pivotally mounted intermediate 35 its ends on the web and having a portion engageable with the drum only when the shoe is applied, cooperating means between one end of said lever and the support for adjusting the "off" position of the unmounted end of the shoe toward the drum, connecting means between the other end of the lever and the free portion of the drum engaging means for adjusting the "off" position of said free portion of the drum engaging means toward the drum and a spring- 40 actuated wedge cooperating with the lever and the web for maintaining the lever and the web 45 in their relatively adjusted positions. 50

11. In braking mechanism, a support, a brake drum, a brake shoe for cooperation with the drum, said shoe comprising a web mounted at one end on the support for pivotal movement 60 and for circumferential movement of the drum, a flange provided with a lining and extending over the major portion of the web and being secured to the portion of the web from an intermediate point to the free end of the web and so associated with the remaining portion of the web that it is free to move relatively to the web and outwardly toward the drum, means operable by circumferential movement of the web when the shoe is applied to the drum for forcing the free portion of the lining carrying flange toward the drum, and automatically operable 65 means for maintaining the "off" position clearance between the drum and the lining carried by the flange substantially constant, said means 70

being so associated with the secured portion of the flange and the free portion of the flange that both portions will have their "off" positions simultaneously adjusted toward the drum as wear occurs.

12. In braking mechanism, a support, a brake drum, a brake shoe for cooperation with the drum, said shoe comprising a web mounted at one end on the support for pivotal movement and for circumferential movement of the drum, a flange provided with a lining and extending over the major portion of the web and being secured to the portion of the web from an intermediate point to the free end of the web and so associated with the remaining portion of the web that it is free to move relatively to the web and outwardly toward the drum, means operable by circumferential movement of the web when the shoe is applied to the drum for forcing the free portion of the lining carrying flange toward the drum, a fixed stop carried by the support adjacent the free end of the web, a lever pivoted on the web and adapted to engage the stop when the shoe is a predetermined distance from the drum, means controlled by the wear of the lining for causing relative movement between the web and the lever, means for automatically maintaining the lever and the web in their relatively adjusted positions, and means operable by the lever when moved relatively to the web for moving the free portion of the flange outwardly toward the drum.

13. In braking mechanism, a support, a brake drum, a brake shoe for cooperation with the drum, said shoe comprising a web mounted at one end on the support for pivotal movement and for circumferential movement of the drum, a flange provided with a lining and extending over the major portion of the web and being secured to the portion of the web from an intermediate point to the free end of the web and so associated with the remaining portion of the web that it is free to move relatively to the web and outwardly toward the drum, means operable by circumferential movement of the web when the shoe is applied to

the drum for forcing the free portion of the lining carrying flange to the drum, a fixed stop carried by the support adjacent the free end of the web, a lever pivotally mounted intermediate its ends on the web and having one end adapted to engage the stop when the shoe is a predetermined distance from the drum, means controlled by the wear of the lining for causing the lever to pivot relatively to the web, means for maintaining the lever and the web at their relatively adjusted positions, and connecting means between the other end of the lever and the free portion of the flange for moving the latter outwardly toward the drum when the lever is moved as a result of wear of the lining.

14. In braking mechanism, a support, a brake drum, a brake shoe for cooperation with the drum, said shoe comprising a web mounted at one end on the support for pivotal movement and for circumferential movement of the drum, a flange provided with a lining and extending over the major portion of the web and being secured to the portion of the web from an intermediate point to the free end of the web and so associated with the remaining portion of the web that it is free to move relatively to the web and outwardly toward the drum, means operable by circumferential movement of the web when the shoe is applied to the drum for forcing the free portion of the lining carrying flange toward the drum, a fixed stop carried by the support adjacent the free end of the web, a lever pivotally mounted intermediate its ends on the web and having one end adapted to engage the stop when the shoe is a predetermined distance from the drum, means controlled by the wear of the lining for causing the lever to pivot relatively to the web, spring-actuated wedge means for holding the lever in adjusted position with respect to the web, and connecting means between the other end of the lever and the free portion of the flange for moving the latter outwardly toward the drum when the lever is moved as a result of wear of the lining.

STEVE SCHNELL.
